Primary Examiner — Lakiya G Rogers*Assistant Examiner* — Harold E Blackwell, II(74) *Attorney, Agent, or Firm* — Kilpatrick Townsend & Stockton LLP(57) **CLAIM**

The ornamental design for a snow guard, as shown and described.

DESCRIPTION

FIG. 1 is a perspective top view of a snow guard. FIG. 2 is a rear view of the snow guard of FIG. 1. FIG. 3 is a front view of the snow guard of FIG. 1. FIG. 4 is a left side view of the snow guard of FIG. 1. FIG. 5 is a right side view of the snow guard of FIG. 1. FIG. 6 is a top view of the snow guard of FIG. 1; and, FIG. 7 is a bottom view of the snow guard of FIG. 1. The broken lines form no part of the claimed design. The dash-dot-dash broken lines immediately adjacent the shaded areas represent the bounds of the claimed design and form no part of the claimed design.
